(57) **CLAIM**

The ornamental design for a cylinder-shaped computer memory device, as shown and described.

DESCRIPTION

FIG. 1 is a three dimensional exploded view of a cylinder-shaped computer memory device in accordance with the present invention;

FIG. 2 is a front exploded view thereof;

FIG. 3 is a rear exploded view thereof;

FIG. 4 is a side exploded view thereof;

FIG. 5 is a top plan view thereof;

FIG. 6 is a bottom plan view thereof;

FIG. 7 is a front assembled view thereof; and,

FIG. 8 is a three dimensional view thereof wherein the top portion is shown separately to show engagement to a laptop computer.

The broken line matter is for illustrative purposes only and forms no part of the claimed design.

1 Claim, 6 Drawing Sheets
